ELECTRIC WAVE GUIDE

Edward Cecil Cork and Michael Bowman-Manifold, Ealing, London, England, assignors to Electric & Musical Industries Limited, Hayes, England, a company of Great Britain

Application April 18, 1945, Serial No. 589,068
In Great Britain September 1, 1942

Section 1, Public Law 690, August 8, 1946
Patent expires September 1, 1962

5 Claims. (Cl. 250—33.63)

1

This invention relates to electric wave guides for the transmission of TM or transverse magnetic type electromagnetic waves.

The invention is concerned with wave guides consisting of hollow conductors, the electromagnetic energy being transmitted through a dielectric medium within the conductors.

For many purposes it may be required to employ a guide which at positions along its length contains different dielectrics. Where such a guide is required it is found that the presence of different dielectrics can give rise to undesirable reflections of the electromagnetic energy at the dielectric interfaces.

It is the object of the present invention to provide an improved construction of wave guide having portions filled with different dielectrics in which reflection of energy at the boundary between the different dielectrics is substantially reduced or eliminated.

According to one feature of the invention a wave guide for the transmission of electromagnetic waves having an electric component of the field therewithin along the axis of the guide and hereafter generally referred to as waves of the E or TM type is provided having portions filled with different dielectrics wherein the transverse dimensions of the guide at the boundary between said different dielectrics are so related to the dielectric constants of the said different dielectrics and to the frequency of the E or TM type waves that reflection of said waves at said boundary is substantially reduced or eliminated.

The invention is of particular use where it is desired to employ two sections of wave guide of different size, one of the sections being filled, for example, with a solid dielectric and the other section having an air dielectric. It is known that two guides of different transverse dimensions employing the same dielectric can be connected together and matched to avoid reflection by joining the two sections of guide by an intermediate section in which the transverse dimensions thereof slowly change from the section of larger size to the section of smaller size. If, for example, the two sections of the guide are of circular form in cross-section then the two sections may be connected together by means of a conical section having an angle of taper not exceeding about 10°. Where such a construction is employed and one of the sections of the guide is filled with a different dielectric from the other section of the guide, then it is possible in accordance with the present invention to arrange the boundary between the different dielectrics at a suitable posi-

2

tion along the section having the slowly changing diameter so that reflection is substantially eliminated.

In order that the said invention may be clearly understood and readily carried into effect, it will now be more fully described with reference to the accompanying drawings, in which:

Figure 1 illustrates a wave guide filled with different dielectrics, and

Figure 2 of the drawings illustrates the invention as applied by way of example to a wave guide aerial employing sections of wave guide of different diameter.

As shown in Figure 1, the reference numeral 3 indicates a wave guide which is of circular form in cross-section and is designed for the transmission of electromagnetic waves of the so-called E₀₁ mode. The first subscript indicates the order, that is, the number of full period variations of

20 radial component of the field along angular coordinates within the guide and the second subscript the mode; that is, the number of half period variations of angular component of field along radial coordinates within the guide. Thus

25 a TM wave of the mth order and nth mode is represented by E_{mn}. In the form shown in Figure 1 the guide 3 has a constant cross-sectional area and one portion of the guide is filled with a dielectric K₁ which dielectric may be air and another portion of the guide is filled with a solid dielectric K₂ such as that known by the trade name "Polystyrene." The boundary between the different dielectrics is arranged in the plane S—S', which is located at right-angles to the axis of the guide. The arrangement is identical

35 with the system formed by joining two wave guides of the same diameter but having different dielectric materials. To insure a match between the two wave guides, it is necessary that the radius of the guide 3, the dielectric constants 40 and the frequency of the waves transmitted should be related so that a minimum of reflection occurs at the surface SS'.

It is known that wave propagation in a guide 45 may be regarded as a case of reflection, there being a certain system of sources inside the guide and the total field inside the guide being the sum of the impressed and reflected fields. For example in Figure 1, the wave reaching the boundary SS' is the sum of the fields of the waves reflected from the surface of the guide enclosing the medium K₁. Such reflected waves reach the

50 boundary SS' at an angle to the normal to the SS' determined by the dimensions of the guide. 55 This angle is important in that it determines the

amounts of transmission and reflection that occur at SS'. In particular, in accordance with this invention, when the wave is of transverse magnetic or TM type and the angle is equal to the Brewster or pseudo-Brewster angle, then reflection is wholly or substantially eliminated and the wave is effectively totally transmitted into the medium K_2 . This is then equivalent to having the guide containing K_1 matched to the guide containing K_2 .

The above explanation is based upon well known optical theory. A more detailed discussion where the optical theory is identified with a general electromagnetic theory is to be found in Schelkunoff's "Electromagnetic Waves" (published in 1943) pages 251-254 while the use of the Brewster angle to obtain impedance matching at a surface of discontinuity is referred to on page 253.

If instead of the wave guide 3 having a constant diameter as shown in Figure 1, two sections of the wave guide are employed having different diameters, then as stated above it is known that these two sections can be matched without introducing appreciable reflection providing the two sections of different diameter are joined by an intermediate section having a slowly changing diameter. Consequently, in the case where the two sections of different diameter are filled with different dielectrics a minimum of reflection will occur at the boundary between the two dielectrics providing the boundary is located at a position where the radius of the intermediate section has a value in accordance with the above considerations.

Figure 2 of the drawings illustrates the invention as applied to a wave guide aerial having two sections of different diameter joined by an intermediate section. As shown in Figure 2 the section of guide of larger diameter is indicated by the reference numeral 4 and the section of smaller diameter is indicated by the reference numeral 5 and constitutes the aerial section of the guide. Energy can be radiated from the aerial or picked up by the aerial via a slot 6 provided on the circumference of the guide and, in the construction shown, in order that the section 5 can have a minimum diameter and at the same time the slot 6 can be protected against the ingress of foreign matter, the section 5 is filled with a solid dielectric indicated at 7, such as the material known by the trade name "Polystyrene." In order to provide a match between the sections 4 and 5 of different diameter an intermediate section 8 is provided of conical form having a small angle of taper. Providing the angle of taper is sufficiently small, substantially no reflection will occur at the intermediate section. In accordance with the invention the boundary between the solid dielectric 7 and the air dielectric of the section 4 is so disposed that it is located at a position where the radius of the section 8 has a value as defined by the above theory. In this manner a minimum of reflection will occur at said boundary. The end of the section 5 is closed by a metal disc 9 to prevent the escape of energy at the end of the section 5, and in order to prevent currents flowing on the outside of the section 5, the latter is effectively earthed at a plurality of spaced points by providing two pairs of segmental fins 10 of conducting material secured to bands 11, in turn attached to the outer surface of the guide 5, the members 10 extending around the periphery of the guide for about 90°. These members 10 are proportioned so that, in

effect, they have a radial length equivalent to a quarter of a wavelength of the transmitted waves. The fins of each pair are also spaced apart by a distance of approximately a quarter of a wavelength.

The invention is not limited to the above mentioned examples but may, on the contrary, be applied to any transverse magnetic type of wave and any cross section of wave guide provided

that the dimensions of the wave guide are such as to cause the component waves to fall on the boundary at the Brewster angle. In other words, the dimensions of the guide must be such that the impedance of the guide on one side of a transverse boundary surface is equal to the impedance on the other side of the transverse boundary surface.

What we claim is:

1. A wave guide aerial for the radiation or reception of electromagnetic waves having a component of electric field along the axis of said guide, said guide having portions filled with different dielectrics, said wave guide having an aperture on one side thereof whereby the interior of said guide is coupled to the exterior thereof, a discontinuity in the dielectric within said guide at the position of said aperture, a portion of said exterior serving as radiating means, said wave guide being of reduced transverse dimensions in the portion which serves as a radiating means, the transverse dimensions of said guide slowly decreasing from the section of larger size to the section of reduced size, a plane boundary between said different dielectrics being disposed within the portion of said guide which is of slowly decreasing size, transverse dimensions of the guide at the boundary between said different dielectrics being so related to the dielectric constants of the different dielectrics and the frequency of the waves that reflection of said waves at said boundary is substantially reduced.

2. A wave guide aerial for the radiation or reception of electromagnetic waves having a component of electric field along the axis of said guide, said guide having portions filled with different dielectrics, said wave guide having an aperture on one side thereof whereby the interior of said guide is coupled to the exterior thereof, a discontinuity in the dielectric within said guide at the position of said aperture, a portion of said exterior serving as radiating means, said wave guide being of reduced transverse dimensions in the portion which serves as a radiating means, the transverse dimensions of said guide slowly decreasing from the section of larger size to the section of reduced size, a plane boundary between said different dielectrics being disposed within the portion of said guide which is of slowly decreasing size and means at each end of said radiating portion for inhibiting the flow of current along the exterior of said guide beyond said radiating portion, transverse dimensions of the guide at the boundary between said different dielectrics being so related to the dielectric constants of the different dielectrics and the frequency of the waves that reflection of said waves at said boundary is substantially reduced.

3. A wave guide aerial for the radiation or reception of electromagnetic waves having a component of electric field along the axis of said guide, said guide having portions filled with different dielectrics, said wave guide having an aperture on one side thereof whereby the interior of said guide is coupled to the exterior thereof, a discontinuity in the dielectric within said guide

at the position of said aperture, a portion of said exterior serving as radiating means, said wave guide being of reduced transverse dimensions in the portion which serves as a radiating means, the transverse dimensions of said guide slowly decreasing from the section of larger size to the section of reduced size, a plane boundary between said different dielectrics being disposed within the portion of said guide which is of slowly decreasing size and means at each end of said radiating portion for inhibiting the flow of current along the exterior of said guide beyond said radiating portion, each of said means including a pair of conductive fins on said guide spaced apart a distance equal to a quarter of the operating wavelength and extending away from the surface of said guide a distance equal to a quarter of the operating wavelength, transverse dimensions of the guide at the boundary between said different dielectrics being so related to the dielectric constants of the different dielectrics and the frequency of the waves that reflection of said waves at said boundary is substantially reduced.

4. A wave guide in the form of a hollow conductive tube for the transmission of electromagnetic waves of the transverse magnetic type and comprising two sections having different trans-

verse dimensions, an intermediate section joining said first two sections, the transverse dimensions of the latter section slowly decreasing from the section of larger size to the section of smaller size, and different dielectrics disposed within said first two sections and extending into said intermediate section with a plane boundary between said different dielectrics disposed within said intermediate section.

10 5. The wave guide claimed in claim 4 having a circular internal cross section.
